UNITED STATES PATENT OFFICE.

THOMAS M. RINEHART, OF PITTSBURG, PA., ASSIGNOR TO HIMSELF, FREDERICK WINTER, AND ADAM GOODWIN, OF SAME PLACE.

ROTARY ENGINE.

SPECIFICATION forming part of Letters Patent No. 280,766, dated July 3, 1883.

Application filed March 31, 1883. (No model.)

To all whom it may concern:

Be it known that I, THOMAS M. RINEHART, of Pittsburgh, in the county of Allegheny and State of Pennsylvania, have invented a new and useful Improvement in Rotary Engines; and I do hereby declare the following to be a full, clear, and exact description thereof.

My invention relates to an improvement in rotary engines in which a reciprocating is changed to a rotary movement by means of a revolving cylinder suitably journaled, provided with a piston having a reciprocating movement, in connection with devices for changing the reciprocating to a rotary movement, so as to cause the cylinder to revolve on its axis; and it consists in certain novel constructions and combinations of the devices, as will hereinafter more fully appear.

I will now describe my invention, so that others skilled in the art may manufacture and use the same, reference being had to the accompanying drawings, forming part of this specification, in which—

Figure 1 is a side elevation of my improved engine. Fig. 2 is a longitudinal vertical section of the same, showing the piston at the end of its stroke. Fig. 3 is a like view, showing the piston at the middle of its stroke. Fig. 4 is a cross-sectional view of one of the pillow-blocks, showing the steam-ports.

Like letters of reference indicate like parts wherever they occur.

In the drawings, *a* represents the frame of the engine, which is planted on a suitable foundation.

At one end of the bed or frame *a* are bolted or otherwise secured two pillow-blocks, *b* *c*. Journaled in these pillow-blocks, by means of the hollow necks *d* *e*, is the cylinder *f*, in which is the piston-head *g*, connected with the piston *h*, which extends through the neck *d* on the cylinder-head into the tube or casing *i*, in which is a square groove or way, *k*. Secured on the piston *h* at this point is a square collar, *l*, which fits and slides in the way *k*. The casing *i*, which is attached to the cylinder-head, is supported by and journaled in a third support or pillow-block, *m*, and is securely bolted or otherwise attached to the end of the neck *d*, so that the cylinder *f* shall revolve with the casing. From the collar *l* the piston-rod or

shaft *k'* extends through the casing *i* into a stationary cylinder, *n*, which is bolted to the frame or bed *a*. At this end of the piston, secured thereto, is a block or collar, *o*, from which extends a pin, *p*, which fits and travels in a groove, *q*, in the inside face of the cylinder. This groove *q* extends, commencing from the bottom of the cylinder *n*, at one end of the same, diagonally upward to the top of the cylinder at the other end of the same, and thence diagonally downward to the place of beginning, being ellipsoidal in form, its purpose being to impart a rotary movement to the reciprocating piston or shaft *h*. The pin *p*, following the groove *q*, gives half a rotation to the piston in its forward stroke, and completes the rotation on its backward or return stroke.

In the pillow-blocks *b* and *c* are steamways *r* and *s*, which open into a valve-chamber, *t*, in each of the two pillow-blocks *b* and *c*. These chambers *t* are next to and are closed by the outer circumference of the hollow necks *d* and *e*, which open into the cylinder *f* and extend around the same about the distance of one-fourth of the circumference. In the pillow-blocks, on the opposite side from the chambers *t*, are similar chambers, *u*, which are for the exhaust-steam from the cylinder and discharge into the exhaust-ways *v*. Opening through the necks *d* and *e* are steam-ports *x* and *y*, through which the live steam and the exhaust-steam alternately pass, the two ports being on opposite sides—that is, when the port *x* is at one side or toward the bottom of the engine, receiving steam from the chamber *t* in the pillow-block *b*, the steam-port *y* is at the other side or toward the top of the engine, discharging exhaust-steam into the exhaust-chamber *u* in the pillow-block *c*. Leading from the boiler are steam-pipes *z*, which carry steam to the steamways *r* and *s*.

Secured to the end of the neck *e* is a band-wheel, *z'*, which is connected by a band, *y'*, with the band-wheel *x*, which in turn operates the governor *v'*, which is connected with a valve in the steam-supply pipe, in the usual manner.

On the outer face of the rotating cylinder *f* is cast or otherwise secured or formed the fly-wheel *w'*, and around the casing *i* is the band-wheel *w*.

The operation is as follows: The different

parts being in the position shown in Fig. 2, live steam from the boiler, passing through the pipe *z*, enters the steamway *r* in the pillow-block *b*, and thence passes into the chamber *t* 5 and through the port *x* into the hollow neck *d*, which opens into the cylinder *f* and drives the piston-head *g* to the other end of the cylinder; the exhaust-steam on the other side of the piston-head at the same time, passing into the chamber *u* through the port *y*, escapes through the steamway *v* in the pillow-block *c*. At the commencement of the stroke of the piston-head the pin *p*, on the collar *o* in the stationary cylinder *n* at the other end of the piston or shaft 15 *h*, is at the top and rear end of the cylinder *n*; but as the shaft moves forward the pin, moving in and being guided by the ellipsoidal groove *q*, causes the shaft or piston and the cylinder *f* to revolve on their axes, giving them, by means 20 of the forward motion, a half-revolution, which revolution is completed by the return-stroke. This return-stroke is caused by the live steam entering the cylinder through the steamway *s* and chamber *t* in the pillow-block *c* and port 25 *y* in the hollow neck *e*, while the exhaust-steam escapes through the chamber *u* and way *v* in the pillow-block *b*. As the shaft or piston *h* revolves on its axis the square or angular collar *l* in the tube or casing *i*, being unable 30 to turn in the way *k*, causes the casing *i* to revolve on its axis, it being journaled in the pillow-block or support *m*, as already described, and the casing *i* being bolted or otherwise firmly secured to the neck *d* of the cylinder *f*, the cylinder *f* revolves on its axis, it being journaled in the pillow-blocks *b* and *c*, thereby causing the steam-chambers *t* and the 35 ports *x* and *y* to operate as an automatic valve for the supply of steam to the cylinder, and the chambers *u* and ports *x* and *y* to act as an 40 automatic valve for the discharge of the exhaust-steam, and thereby the drive-wheel *w* is caused to revolve, and the power of the engine is applied.

45 My invention as herein described may be modified, so as to adapt the engine to the use of the general form of sliding or puppet valves, by arranging the parts so that the cylinder *n* shall be caused to revolve while the cylinder *f* and casing *i* remain stationary, and the piston *h* has but a direct reciprocating movement.

The advantages of my improvement are—

First. The unequal wearing away of the bottom of the inside surface of the cylinder is entirely prevented. It is a well-known fact that

in reciprocating engines, where the cylinder is in a horizontal position, the movement and weight of the piston-head will gradually wear away the bottom of the inside of the cylinder. 60 It is obvious that on account of the revolution of the cylinder this unequal wearing is prevented by my improvement, as all portions of the inside surface of the cylinder are equally subjected to the weight and wear caused thereby, and this wearing-surface being greatly increased, all portions of the surface being subject thereto, the rapidity of the wear is correspondingly diminished.

Second. The turning-points at the ends of 70 the ellipsoidal groove *q* being at an acute angle, the groove not being in the form of a true ellipse, there is but an inappreciable dead-point at the end of the strokes of the piston, and the piston acts with equal force from the 75 beginning to the end of its stroke, thereby saving a great amount of power which is lost in other forms of reciprocating engines.

Third. While my improved engine retains and increases the power of the positive force 80 of a reciprocating engine, it has also the advantages of a rotating engine, being evenly balanced, and, on account of the revolution of the different parts, the loss of power by weight and friction is greatly diminished.

Having thus described my invention, what I claim, and desire to secure by Letters Patent, is—

1. In a rotary engine, a revolving cylinder 90 suitably journaled and provided with a piston having a reciprocating movement, in combination with a fixed cylinder having an ellipsoidal groove for the reception of a pin on the piston-rod for converting the reciprocating motion of the piston into rotary motion, and 95 devices, substantially as described, for communicating the rotary motion to the cylinder, substantially as and for the purposes specified.

2. The combination of the revolving cylinder *f*, provided with a piston and piston-rod having a square collar and a pin, *p*, casing *i*, having a square groove or way, and stationary cylinder *n*, having an ellipsoidal groove for the pin of the piston-rod, substantially as 105 and for the purposes specified.

In testimony whereof I have hereunto set my hand this 28th day of March, A. D. 1883.

THOMAS M. RINEHART.
